UNITED STATES PATENT OFFICE.

WILLIS C. WEBSTER, OF DUBOIS, PENNSYLVANIA.

BALANCE-VALVE.

1,237,981.

Specification of Letters Patent. Patented Aug. 21, 1917.

Original application filed May 1, 1915, Serial No. 25,273. Divided and this application filed October 21, 1915. Serial No. 57,164.

To all whom it may concern:

Be it known that I, WILLIS C. WEBSTER, a citizen of the United States, residing at Du-
5 bois, in the county of Clearfield and State of Pennsylvania, have invented certain new and useful Improvements in Balance-Valves, of which the following is a specification.

My present invention relates to new and useful improvements in valves, being a division of a copending application for balanced valves, filed by me May 1, 1915, and bearing the Serial No. 25,273, the primary object of this invention consisting in the provision of a frictionless balanced valve.

15 A further object of my invention consists in providing a valve of the above described character which, may be opened and closed manually or mechanically.

In accomplishing the above objects, I provide a valve casing divided by a septum or spider formed with a valve seat and a valve having an operating stem projecting beyond the casing and having a fluid pressure passage which is closed when the valve engages 20 the seat, the valve being supported and controlled by means of a plurality of diaphragms secured to the valve and valve casing and forming a number of chambers, communication between the inlet port of the 25 valve and outlet port thereof being established through the valve itself and between certain of these chambers.

A further object of my invention consists therefore in providing a construction by 30 means of which the valve, its stem and its diaphragms may be readily assembled and properly secured in the valve casing.

With these and other objects in view, my invention will be more fully described, illustrated in the accompanying drawing, and then specifically pointed out in the claims which are attached to and form a part of this application.

The drawing is a central, vertical sectional sectional view taken through my improved valve.

Corresponding and like parts are referred to in the following description and indicated in the drawing by the same reference characters.

My improved balanced valve includes a valve body or casing 10 open at its ends and preferably cylindrical in shape, this body, intermediate its length, being divided by a

transverse septum or spider 11 having a 55 plurality of enlarged equalizing passages 12 and formed centrally with a cylindrical bore 13 to receive the cylindrical body portion of a valve seat 14. This valve seat is preferably pressed into place in the bore 13 and at 60 its lower end is provided with a circumferential shoulder 15 which engages the lower face of the septum 11 to insure its proper positioning therein. This valve bushing is formed with a central, cylindrical bore 16 65 which, near its lower end, is formed internally with spaced annular shoulders U-shaped in section, projecting into the bore, the lower of these shoulders projecting to a less extent than the upper to provide spaced 70 frusto-conical valve seats 18 and 19. These seats are preferably, although not necessarily, formed at the same inclination to the longitudinal axis of the bushing and the lower seat is in effect formed in the lower 75 face of the bushing.

Co-acting with the above described valve seat, is a valve proper, indicated as a whole by the numeral 20. This valve includes a cylindrical head portion 21 and stem portion 80 22 having threaded connection with each other, as shown at 23. The head portion 21, which is equal in diameter to the bore 16 formed in the bushing, is reduced to provide spaced frusto-conical shoulders or seat 85 portions 24 and 25 adapted to engage the seats 18 and 19, respectively, of the bushing and to further provide an intermediate cylindrical portion 26. Above the upper of these seat portions 24, the valve is provided 90 with a further reduced cylindrical portion 27 upon which the threads are cut which engage in the internally threaded socket of the lower end of the stem portion 22 of the valve, the lower end of such stem portion 95 being exteriorly beveled, as shown at 28, to meet the reduced cylindrical portion 27 of the valve head. As a result, when the valve and stem are assembled, the valve is capable of being opened until the beveled lower end 100 28 of the stem portion 22 engages the upper face of the upper shoulder 18, there being an annular chamber between the upper face of this shoulder and the beveled face 28 when the valve is closed or open, due to a 105 difference in the inclinations of the beveled end of the stem and the upper face of the shoulder 18. The valve stem proper pro-

jects, when the valve is closed, nearly to the upper end of the valve casing and is reduced at a point somewhat above the septum 11 to provide an annular shoulder 29 and has its 5 terminal further reduced and externally threaded, as shown at 30. The valve and its stem portion are provided with an axially formed bore 31. This bore, as a rule, opens through the lower end of the valve and at 10 its upper end extends beyond the annular shoulder 29 and nearly to the reduced terminal 30 of the valve stem, a plug 32, slotted at 33 to receive a screw driver, being employed to close the lower end of the bore 31 15 when the valve is in use. This bore, as will be later apparent, forms a portion of the fluid passage through the valve and its diameter may, therefore, be varied to suit the use to which the valve is to be put. The 20 valve proper is further provided with a plurality of diametrically formed bores or passages 34 which intersect the bore 31 and which, at their outer ends, open into the cylindrical face 26 of the valve. The valve or 25 stem portion thereof is, in like manner, provided with one or more diametrically formed bores or passages 35 intersecting the axial bore 31 near its upper end, that is, at a point intermediate between the shoulder 30 29 and reduced terminal 30 of the valve stem.

As the entire fluid passing through my balanced valve passes through these bores or passages 34 and 35, it will be clear that 35 the sum of the cross sectional areas of the passages of each group, above described, should at least be equal to or preferably exceed the cross sectional area of the main bore or passage 31.

40 A diaphragm 36 is formed centrally with an opening to receive the reduced terminal 37 of the valve and engages against the annular shoulder formed as a result of reducing such terminal, being clamped against 45 this shoulder by a nut 38. A cotter pin or other suitable anchoring device 39 is passed through this nut, through the terminal of the valve and through an opening formed in the plug 32 to securely anchor both 50 the plug and nut against displacement. As clearly shown, the valve casing 10 has its lower edge reduced in thickness to provide an annular seat 40 to receive the peripheral edge of the diaphragm, this seat being provided 55 with a circumferential channel in which a metallic packing ring 41, preferably of soft lead, is positioned to prevent leakage of fluid past the edge of the diaphragm. A clamping ring 42 is positioned against the 60 outer face of the diaphragm and is secured in place by a bonnet 43 which is threaded into the open lower end of the valve casing. This bonnet is formed with a vent port 44 and a stop 49 spaced somewhat below the 65 lower end of the valve stem and engageable

by the valve stem upon opening of the valve to a certain extent to prevent further movement of the valve.

The upper portion of the valve casing 10 is cut away interiorly to provide spaced annular shoulders 50 and 51, the interior diameter of the casing, above the shoulder 50, as a result, being greater than the interior diameter of the main body of the casing, while that above the shoulder 51 is greater than 75 that above the shoulder 50. A diaphragm 52 is formed centrally with an opening to receive the reduced upper end of the valve stem, this diaphragm seating centrally upon the annular shoulder 29 and peripherally 80 upon the shoulder 50, this latter shoulder having its face channeled to receive a metallic packing ring. A sleeve 54 surrounds the stem portion of the valve 21, seating at its lower end upon the diaphragm 52 and at its 85 upper end supporting a further diaphragm 55. The wall of this sleeve is provided with openings 56 adapted to align with the ends of the passages 35 and is further provided in its inner face with a longitudinally extending channel 57 to receive the end of a pin 58 extending radially from the stem portion of the valve, this pin and channel serving to insure proper positioning of the sleeve 54 about the stem portion of the valve to 90 bring its openings 56 into alignment with the ends of the passages 35.

A ring or collar 59 fits closely within that portion of the valve casing above the shoulder 50, seating at its lower edge upon the peripheral edge portion of the diaphragm 52 and at its upper edge receiving the peripheral edge of the diaphragm 55. This ring or collar is provided at one side with a port or passage 60 which aligns with a port or 100 passage 61 formed in the valve casing, this latter port or passage constituting either the inlet or outlet port of the valve, as preferred. In order to insure proper alignment with the ports 60 and 61, the collar 59 105 is provided, in its outer face, with a longitudinal groove or channel 62 to receive the extended end of a pin 63 which projects radially from the wall of the valve casing. The upper end of the collar 59 is externally 110 reduced to form a shoulder 64 in the same horizontal plane with the shoulder 51 in order that a metallic packing ring 65 may be seated between the ring and valve casing 115 and below the diaphragm 55.

120 A clamping ring 66 is positioned directly above the diaphragm 55, engaging the peripheral edge of the diaphragm to hold it in place and is secured in place by a bonnet 67 closing the upper end of the valve casing. 125 A nut 70 is threaded upon the threaded terminal 30 of the stem portion of the valve 22 to clamp the central portion of the diaphragm 55 against the upper end of the sleeve 54 and to, consequently, hold the cen- 130

tral portion of the diaphragm 52 between the lower end of such sleeve and the shoulder 29, this nut being secured against displacement from the stem portion of the 5 valve by a cotter pin 71 or equivalent fastening device.

It will be apparent that the diaphragms 36, 52 and 55 divide the valve casing into a plurality of chambers 74, 75, 76 and 77 and 10 that the valve 20 is adapted, when opened, to establish communication between the chambers 75 and 76. A duct or passage 78 is cored through the wall of the valve casing to provide an inlet or outlet passage, according 15 to whether the passage 61 is utilized as an inlet or outlet passage and, for the sake of convenience, this duct is preferably so formed that its outer end is in alinement with the passage 61 in order that the valve 20 may be readily inserted in a pipe line. The 20 passages 61 and 78 extend through externally threaded nipples 79 which, in connection with the coupling devices 80, provide means for connecting the valve to pipe 25 sections.

Preferably, the clamping ring 42, collar 59 and clamping ring 66 are each provided interiorly with an annular rib or shoulder 81 by means of which they may be readily 30 grasped and withdrawn from the valve casing in case the valve is being disassembled for repairs or cleaning purposes.

In order that the valve may be accurately balanced, under all conditions, it is necessary 35 that the areas of the surfaces of the diaphragms, which are exposed to pressure, be the same. By referring to the drawings, it will be seen that the diaphragms 52 and 55 are exactly equal to each other in area and 40 that, for this reason, any pressure in the chamber 76, whether it enters through the valve or through the alined passages 60 and 61, will in no way tend to either open or close the valve, having no effect thereon. 45 This is due to the fact that the pressure exerted against the diaphragms 52 and 55 is equal and that the pressure in the chamber 76, acting in the bore 31 of the valve, acts equally against the upper closed end of the 50 bore, against the plug 32, closing the opposite end, and against opposite sides of the passages 34 and 35, with the result that such pressure in no way tends to either open or close the valve.

Assuming that there is any pressure in the 55 chamber 75, it will be clear that the fluid in such chamber will act equally against both diaphragms 36 and 52 with no effect on the valve. It will, therefore, be clear that any 60 pressure in the chamber 75, when the valve is closed, will have absolutely no effect, tending to either open the valve or to hold it more closely to its seat. Again, it will be clear that the fact will be the same when 65 the valve 20 is open, as the valve will then

be subject to a slight downward pressure against its conical faces 23 and 24, which pressure is balanced by an upward pressure against its face 28.

The bonnet 67 has an atmospheric vent or 70 passage 86, whereby the upper face of the diaphragm 55 is, at all times, subjected to atmospheric pressure and is provided centrally with an opening and the stem portion 22 of the valve 20 is formed with a reduced 75 extension 87 projecting through this opening and providing a means for manually operating the valve. Furthermore, by means of this extended portion 87 of the stem, it will be apparent that the valve may be operated by any suitable mechanism, such as a centrifugal governor or by means of solenoids, electro-magnets or other equivalent devices.

The operation of the valve will be readily 85 understood by reference to the drawings. Under normal circumstances, that is, with the valve closed, the valve will be held to its seat but without any real application of force tending to prevent its unseating, irre- 90 spective of the pressures which it is controlling, due to the fact that all fluid, under pressure, entering the chamber 75 has no effect either to seat or unseat the valve and that all pressure in the chamber 76 likewise 95 has no effect upon the valve. It will, therefore, be clear that if the least inward pressure is applied to the stem the valve will be moved to open position, the amount of its opening being of course dependent upon the 100 force applied. As soon as the valve has partially opened, fluid under pressure entering from the chamber 75 may pass upwardly between the faces 19 and 18 of the valve seat and faces 25 and 24 of the valve into the 105 passages 34 and so into the main passage 31 of the valve. From this passage, the fluid escapes through the alined ports or passages 35 and 56 to the chamber 76 and so from the valve through the outlet passage 61. If 110 the force applied to the stem is removed, the valve will close, thereby shutting off all flow of fluid therethrough.

A number of advantages which my valve structure possesses over balanced valves of 115 the types now in use will be readily apparent from the foregoing description. Many of the so-called balanced valves require considerable effort for their opening and closing, due to friction between the parts, valves 120 of the piston type being chief among them. Again, many valves of the so-called balanced type depend in their action, either wholly or partially, upon springs which balance the valve only in one position and, with 125 use, require constant adjustment and which also deteriorate and require renewed tensioning. All of these difficulties are done away with by my valve structure.

Furthermore, I have provided a valve 130

which, with slight modifications, may be controlled either manually or mechanically. Again, while many of the so-called balanced valves are balanced by in-coming pressures 5 they are not for out-going pressures or the reverse, or if balanced by both such pressures, they are balanced only when these pressures bear certain definite relations to each other, or only when the valve is closed 10 or when opened.

It is obvious that many minor changes 15 may be made in the details of construction, without in any way affecting the proper operation of my improved valve mechanism and I do not, therefore, wish to in any way limit myself to such details, reserving the right to make any changes, within the scope 20 of the appended claims, without in the slightest degree departing from the spirit of my invention.

Having thus described the invention, what is claimed as new is:

1. A valve including a casing, diaphragms 25 extending across the casing near the ends thereof and exposed at their outer sides to atmospheric pressure, the casing being formed between the diaphragms with an inlet and an outlet port, an additional diaphragm dividing the casing between the 30 ports, and a valve secured to all of the diaphragms and controlling passage of fluid from the inlet port through the added diaphragm to the outlet port.

2. A valve including a valve casing provided 35 adjacent its ends with diaphragms exposed at their outer surfaces to atmospheric pressure, the casing being provided between the diaphragms with an inlet and an outlet port, an additional diaphragm 40 dividing the casing between the ports, a valve seat between one of the first diaphragms and the additional diaphragm, and

a hollow reciprocally mounted valve carried by all of the diaphragms and adapted to establish communication between the ports 45 through the added diaphragm and to shut off such communication when in engagement with its seat.

3. A valve including a casing having inlet and outlet ports, a pair of diaphragms extending across the casing and both subjected upon their outer surfaces to atmospheric pressure and one subjected upon its inner surface to fluid pressure through the inlet port and the other upon its inner surface to 55 fluid pressure through the outlet port, an additional diaphragm subjected upon its opposite faces to pressures from both ports, and a valve secured to and movable with all 60 of the diaphragms and capable of establishing or cutting off communication between the ports.

4. A valve including a casing open at its ends, provided adjacent its ends with inlet and outlet ports and between the ports with a web formed with openings and with a valve seat, a diaphragm fixed across the casing between the web and one of the ports, diaphragms positioned against the end portions of the casing, bonnets fixed to the end 70 portions of the casing and clamping the last named diaphragms in place, each of the bonnets being formed with an atmospheric port and one of the bonnets being formed with a central bore, a valve fixed to all of the diaphragms and having a passage adapted in one position to establish communication between the ports and in another position to be closed through engagement of the valve with the valve seat, and a stem extending 75 from the valve and fitting closely in the bore of the bonnet.

In testimony whereof, I affix my signature.
WILLIS C. WEBSTER. [L.S.]
